PAINT BRUSH AND BUCKET HOLDER FOR LADDERS

Filed Feb. 18, 1928

A. J. Trimble

By Watson E. Coleman
Attorney

UNITED STATES PATENT OFFICE

ARCH J. TRIMBLE, OF PRATT, WEST VIRGINIA, ASSIGNOR OF ONE-HALF TO G. H. CABELL, OF PRATT, WEST VIRGINIA.

PAINTBRUSH AND BUCKET HOLDER FOR LADDERS

Application filed February 18, 1928. Serial No. 255,408.

This invention relates to devices for supporting buckets and paint brushes on ladders, and the general object is to provide a very simple device for this purpose having a rung-5 engaging hook so formed as to also engage the side of the ladder and having a bucket bail holding portion and a brush holder.

A further object is to provide a device of 10 this character which is so formed that the handle of the brush is yieldingly clamped in place so that it cannot slide out accidentally and slip into the bucket.

A still further object is to so construct the 15 device that it may be applied upside down upon a bucket to support a paint brush therein.

Other objects will appear in the course of the following description.

My invention is illustrated in the accompanying drawing, wherein:—

Figure 1 is a perspective view of my paint pot and brush holding attachment for ladders, the rail of the ladder being shown in dotted lines;

Figure 2 is a front elevation of a portion of the ladder showing my attachment in front elevation applied thereto.

Referring to this drawing, it will be seen that my brush and bucket holder is formed of 30 a single piece of small metal rod or heavy wire sufficiently strong and rigid so that it will not accidentally become bent out of shape under ordinary usage. The metal rod or wire is bent at one end to provide an upwardly extending U-shaped portion 10 adapted to engage over the rung *a* of the ladder *A*, one of the legs of this U-shaped portion extending downward behind the rung and being provided with an upwardly bent hook 11 35 for a purpose to be later stated.

The wire extends at right angles to the forward leg of the hook 10, as at 12, and then is bent sharply inward or at right angles to the portion 12, as at 13. This forms a ladder 45 rail embracing portion, and from the portion 13 the wire or rod extends laterally outward, as at 14, at right angles to the portion 13, and this portion 14 is formed with a depressed loop 15 designed to receive the bail 50 of the paint bucket. Beyond the loop or de-

pressed portion 15 the wire is carried straight outward and then is bent to provide a plurality of coils 16 spaced from each other to an extent sufficient to permit the handle of a brush to be inserted between the convolutions of the wire and at the end of the coil the wire is formed to provide the upwardly opening hook 17. The hook portions 11 and 17 do not become effective when the device is applied upon a ladder, as shown in Figure 1, but they permit the device to be inverted upon a paint can or bucket and under these circumstances the hooks 11 and 17 will fit down over the wall of the side of the can or bucket to thus support the holder and the brush may then be supported within the can. Thus while at work the holder will be used for supporting a brush and the can upon a ladder and permitting the easy removal of the brush from the can, etc., and when the work is over or pretermitted the holder is taken from the ladder, inverted upon the can, and the brush supported within the can, as described.

It will be seen that my device supports the brush under all circumstances and prevents the brush from slipping down deep into the can and the handle and the body of the brush becoming covered with paint or the hairs of the brush becoming turned upward. The holder can be entirely covered with rubber or partially covered with rubber, as desired. This applies particularly to the ladder-engaging hook formed of the portion 10. A device constructed in accordance with my invention holds a paint can or bucket outward from the latter so as to place it in the most convenient position for use. The bucket is supported by its bail from the portion 15, while the brush holder supports the handle of the brush with the brush itself disposed within the bucket when the brush is not in actual use.

I claim:—

1. A holder of the character described comprising a main hook portion adapted to engage the rung of a ladder, a lateral angularly inclined extension on said hook for engagement with one of the rails of a ladder, a second extension inclined from said first exten- 95

sion, said second extension having a looped intermediate portion whereby to removably receive a bucket bail, and a resilient brush holding member outstanding from said second extension, said brush holding member being adapted to hold a brush dependingly within the bucket.

2. A holder of the character described comprising a main hook portion, adapted to engage the rung of a ladder, a second hook secured to said main hook and positioned in inverted relation thereto, a lateral angularly inclined extension secured to said main hook, a second extension angularly inclined from said first extension and adapted to cooperate therewith for engagement about one of the side rails of a ladder, a third extension secured to said second extension and outwardly inclined therefrom, a depending loop member secured to said third extension and positioned intermediate the ends thereof, resilient brush holding means secured to said third extension, and a third hook secured to the opposite end of said brush holding means, said loop being adapted to removably receive the bail of a paint bucket when the main hook is positioned on the rung of a ladder, said second and third hook members being adapted to removably engage the rim of a paint bucket upon removal of the holder from the ladder whereby to dependingly hold a paint brush in a paint bucket.

In testimony whereof I hereunto affix my signature.
